UNITED STATES PATENT OFFICE.

LAWRENCE E. JOHNSON, OF BOSTON, MASSACHUSETTS, ASSIGNEE TO ELLERY C. WRIGHT, OF BOSTON, MASSACHUSETTS.

LAST.

1,164,686.

Specification of Letters Patent. Patented Dec. 14, 1915.

Application filed May 30, 1914. Serial No. 323,715.

To all whom it may concern:

Be it known that I, LAWRENCE E. JOHNSON, a citizen of the United States, and resident of Boston, county of Suffolk, State of Massachusetts, have invented an improvement in Lasts, of which the following description, in connection with the accompanying drawings, is a specification, like letters on the drawings representing like parts.

The present invention is a hinged last having combined with the hinge and pivotal members, a spring member which will act on the two parts of the last from the same pivotal axis on which the hinge itself permits the swinging movement of the two parts of the last. By this construction both the forepart and the heel part receives the tension of an expansible spring member acting to rock the same upon the pivotal axis outside the two parts of the last, and normally to hold the forepart and heel part in extended position with a firm, even tension with the axis of the hinge as the fulcrum. By this construction I am enabled to apply the spring member directly to the pivot pin constituting the hinge and have the spring itself exert its tension from the pivot pin outwardly on both the forepart and heel part of the last. I am also enabled to apply a spring to a last without materially weakening the wood of the last, cutting it away to receive such spring excepting in the very central part of the last, where the strength and thickness of the wood is greatest, and even here I only need form very slight recesses to receive and apply the spring. Preferably I use a flat leaf hinge of the well-known type shown by Arnold Pat. No. 590,877, and recess the leaves of this hinge in which to fit or apply this spring, providing several coils of the spring about the pivot pin uniting the two leaves of the hinge together, and thus cutting away a portion of the hinge itself, rather than a portion of the last, to make room for the spring. This construction furthermore enables the addition of a spring to be made practically without any increase whatever in the weight of the last, as the leaf members of the hinge are cut away an amount equal or greater than the weight of the material in the spring which I employ.

Referring to the drawings, illustrating a preferred embodiment of the invention, Figure 1 shows a two-part or hinge last of usual

form, wherein my invention is embodied; Fig. 2 is a plan view; Fig. 3 is a cross sectional view; and Fig. 4 is a plan view of the hinge leaves recessed to receive the spring.

As shown in the drawings, a last comprising a forepart 1 and heel part 2 is provided with secant faces 3 and 4 respectively, and the line of cut 5, severing the two parts and permitting the last to be broken or flexed in order to shorten the same and apply it to or remove it from a shoe.

A leaf hinge, comprising a pair of hinge members 6 and 7 adapted to overlap in the center and to receive a pivot pin 8, constituting a well-known type of leaf hinge and two-part last construction, is preferably utilized in my present last. These leaf hinge members are pierced at 9 and 10 to receive bolts or rivets 11 and 12 respectively, as shown in Figs. 3 and 4 to key or anchor the hinge members firmly in the wood of the two parts.

I recess the hinge leaves 6 and 7 slightly about the central portion thereof, as indicated at 13 and 14 (see Fig. 4) leaving a short portion of the pivot pin 8 free from engagement of the overlapping loop members of each hinge leaf, through which the pivot pin 8 passes. These recesses 13 and 14 are of appropriate extent to receive the coils 15 of a spring, which coils encircle the free portion of the pivot pin 8 and said spring has its ends 16 and 17 extending upwardly from said recessed portion to bear against the forepart and heel part respectively of the wood of the last, exerting an expansive pressure "receive" from the coiled spring construction just explained. I desire to slightly recess the secant faces 3 and 4 to receive these upstanding ends 16 and 17 of the spring as shown at 13' and 14', Fig. 3, so as to afford a housing therefor, and a firm lining, and prevent the spring ends from slipping or from being exposed and catching in the lining of the shoe.

With the form of spring shown herein, acting directly from the pivotal member of the hinge in a two-part last, an extremely simple, cheap and efficient construction of hinged last is provided, which affords no points to catch on the lining, is strong, durable, and lasting in mechanical construction, and which exerts a high degree of expansive tension directly from the hinge pin as the fulcrum, thus tending to hold the

joint at all times and prevent wear, racking, or looseness in the pivot and leaf members. Furthermore, the arrangement of the spring acting with the pivot pin as its point 5 through which the tension of the spring is exerted, operates on a correct mechanical principle, and by recessing the leaf spring portions as above explained, I prevent any increase in weight being made to the last by 10 the addition of the spring.

While I prefer to use a round spring, as illustrated in the drawings, it is, of course, feasible to use a flat or leaf spring, fitting the same within the recesses 13 and 14 in the 15 hinge plates, and permitting the free ends of the spring to bear upon the forepart and heel part of the last, as will be readily understood.

Having described my invention, what I 20 claim as new and desire to secure by Letters Patent is:

A hinge last, comprising a heel part, a forepart, and a connecting hinge composed of oppositely extending leaf members arranged respectively in said forepart and heel 25

part, coöperating parts on said leaf members to receive and hold a pin, a pin uniting said leaf members and constituting the pintle on which the last parts are adapted to swing, each leaf of said hinge having oppositely located recesses adjacent the pin adapted to receive the coils of a spring, and an expansible coiled spring having its coils fitted closely about said pin and substantially filling both of said hinge recesses, the 30 free end portions of the spring extending upwardly and bearing in opposite directions against the forepart and heel part respectively, at points above said pin, whereby the last parts are normally held in extended position by spring tension with the pivot pin as the axis for said spring action.

In testimony whereof, I have signed my name to this specification, in the presence of two subscribing witnesses.

LAWRENCE E. JOHNSON.
